United States Patent Office.

CHARLES A. SLACK, OF FRENCHTOWN, NEW JERSEY.

Letters Patent, No. 86,876, dated February 9, 1869.

IMPROVEMENT IN ALARM-BELLS.

The Schedule referred to in these Letters Patent and making part of the same.

To all whom it may concern:

Be it known that I, CHARLES A. SLACK, of Frenchtown, in the county of Hunterdon, and State of New Jersey, have invented a new and improved Combined Alarm Door-Plate and Bell; and I do hereby declare that the following is a full, clear, and exact description thereof, which will enable others skilled in the art to make and use the same, reference being had to the accompanying drawings, forming part of this specification.

The nature of this invention relates to an improved combination of name-plate, bell, and door-knob; and

It consists in providing the name-plate with a knob, and hanging it to the door, and connecting the same, by a cord, to the trigger of a bell inside of the door, whereby the name-plate serves, also, as a bell-pull; and

It further consists in applying to the arbor of the door-knob, inside of the door, a swinging arm, which is also connected to the trigger of the bell by a cord, which, by the turning of the knob to throw back the spring-bolt, will cause the alarm-bell to strike, and give notice of the entrance of any person, which will be more fully described on reference to the accompanying drawings, in which—

Figure 1 represents an outside view of my improvement attached to a door.

Figure 2, an inside view of the same.

Figure 3, a section on the line $x-x$ of fig. 2.

Similar letters of reference indicate corresponding parts in all the figures.

A represents a name-plate hinged to the door A', and provided with a knob, by which it is adapted to the uses of a bell-pull, to which the cord a is fastened, and which passes through a hole in the door, and is connected by the other end to the bell-trigger b .

B is the bell secured to the stud B'; and

C is the hammer attached to the bent arm c , which swings on the pivot c' .

e is a spiral spring, for throwing back the hammer to strike a blow, after it has been moved around by the trigger against the spring, and disengaged from the said trigger.

d is a swinging tappet, pivoted to the inner end of

the bell-crank c , against which the trigger b works to move the bell-crank, and which swings out of the way of the trigger when it is drawn back to its normal position by the spring f .

h is an arm secured to the shank of the door-knob D, and which is also connected to the trigger b by a cord, a' .

The operation of ringing the bell is performed in a manner similar to that of bells as ordinarily constructed.

By pulling the knob on the plate A, the cord a draws the trigger down against the tappet d on the bell-crank, swinging the latter around against the action of the spring e , until the trigger passes by the tappet, and allows the spring to throw the hammer back and strike a blow on the bell.

When the person attempts to pass through the door, without ringing the bell, by taking hold of the knob of the sliding spring-bolt, and turning the same to draw the bolt back, the arm h swings around, and, by means of its connection with the trigger b , gives a blow on the bell in the same manner.

The connection between the arm h and cord a' is so made that it can be readily disconnected if desired.

I am aware that an alarm-attachment to door-knobs is not new; also, that a hinged door-plate and alarm is known; hence I do not claim either. My door-plate may be stationary or hinged, as the device will operate either way.

Having thus fully described my invention,

What I claim as new, and desire to secure by Letters Patent, is—

The arrangement of the spring-trigger b , pivoted latch d , bell-hammer C, cords a a' , and arm h , connected to the door-knob, all as herein shown, whereby the bell is rung from the same trigger, by either the door-knob D or door-plate knob A, as set forth.

The above specification of my invention signed by me, this 8th day of February, 1869.

CHARLES A. SLACK.
